Application August 17, 1951, Serial No. 16,334

Term of patent 14 years

(Cl. D92—26)

To all whom it may concern:

Be it known that I, Florence S. Hooven, executrix of the last will and testament of Howard D. Hooven, late a citizen of the United States of America and resident of Doylestown, State of Pennsylvania, deceased, a citizen of the United States of America, residing at Doylestown, in the county of Bucks and State of Pennsylvania, have a new, original, and ornamental Design for a Tablecloth invented by the deceased, of which the following is a specification, reference being had to the accompanying drawing, forming a part thereof, in which the figure is a face view of a slightly more than quarter section of the tablecloth, showing his new design, the other three sections being identical with the section here disclosed, arranged in proper relation to

complete the tablecloth. The section disclosed is shown over a dark background to bring out the details of the design.

It is claimed:

The ornamental design for a tablecloth, substantially as shown and described.

FLORENCE S. HOOVEN.
*Executrix of the Last Will and Testament of
Howard D. Hooven, Deceased.*
